SLACK TAKE-UP MEANS FOR IRONER TAPES

Filed June 11, 1952

UNITED STATES PATENT OFFICE

2,682,718

SLACK TAKE-UP MEANS FOR IRONER TAPES

Wayne E. Myers, Cincinnati, Ohio, assignor to
The American Laundry Machinery Company,
Cincinnati, Ohio, a corporation of Ohio

Application June 11, 1952, Serial No. 292,833

4 Claims. (Cl. 38—67)

1

The invention relates to improvements in stripping means for flatwork ironers.

An object of the invention is to provide novel and improved means for preventing the flatwork from adhering to the rolls, and being carried around therewith.

A further object of the invention resides in providing novel and improved means for taking up operating slack and idle slack in stripper tapes now in use in connection with ironing rolls.

Other objects and advantages will be apparent from a study of the following specification, in conjunction with the accompanying drawings, in which:

Fig. 1 shows a four-roll flatwork ironer, the stripping tapes and slack take-up means being shown in full line, and the main features of the ironer in dot-dash line.

Fig. 2 is a view similar to Fig. 1, but showing the rolls in idle position, namely raised from the steam chest.

Fig. 3 is a fragmentary top plan view showing certain slack take-up devices as shown on the left top portion of Figs. 1 and 2.

Fig. 4 is a perspective view, somewhat enlarged, showing one of the devices of Fig. 3.

Fig. 5 is a perspective view showing other slack take-up means as shown on the right end of Figs. 1 and 2.

Referring first, for convenience in further discussion, to the main features of the ironer, Figs. 1 and 2 diagrammatically illustrate a flatwork ironer comprising four rolls 10 in tandem, supported above a steam chest or heated bed 11, the bed being provided with suitable concave portions 11a, each one complementary to a respective roll, as will be familiar to those skilled in the art, so that a flatwork article introduced between roll 10 and chest 11 proceeds in an undulant path between the chest and the successive rolls, and is discharged at the right, whereupon it is usually carried by endless tapes or otherwise to a suitable delivery point, usually to be folded.

As is also familiar to those skilled in the art, flatwork articles have a tendency to adhere to a roll, so as to wrap themselves therearound, and the art has disclosed various devices to prevent this. One common means will be termed "stripper tapes," namely a laterally spaced series of endless tapes, identified herein by reference character 12 which pass over and under the roll assembly, and above the chest, the flatwork being introduced between these stripper tapes and the chest, so that as the work emerges from each

2

zone of contact of a roll with the chest, the work is prevented from turning with the roll. The use of stripper tapes of this character is disclosed, for example in U. S. Patent No. 1,808,764 to 5 Forrest J. Couch. In the present drawings the tapes 12 are supported at their front end by being passed around rotatable spools 13 and at their rear end around a bar 14. Further explanation of the means and method of support and operation of the tapes will be made hereinbelow.

There are two factors which mainly contribute to the existence of undesirable slackness in stripper tapes, and which will be respectively termed herein, for convenience, "transient slack" (or "operating slack") and "idle slack." Transit slack arises from the fact that the tapes are subjected to constantly varying moisture conditions, and the tapes expand and contract in response to such variations. Tape tension increases when the tapes contract, and there may be a permanent stretch induced which is not elastically compensated when the tension decreases. Slack take-up means of various types have previously been devised, but have not been entirely satisfactory. One such means is shown in the aforesaid Couch patent which relies mainly on leverage biased by spring tension, but the tape tension existing when the tapes were under maximum stress caused so much stretch that the lever arms were incapable of entirely taking up the slack. In the present application I have provided improved means for offsetting operating or transient slack, as will appear.

The second factor contributing to slackness in stripper tapes arises from the fact that the set of rolls, when idle, are raised from contact with the heated chest, for example from the position of Fig. 1 to that of Fig. 2. The stripper tapes 12 need no longer follow the undulating path provided by the crests and hollows of the chest, and consequently would droop loosely from the upper support, and under such conditions the tapes had a tendency to become laterally displaced, or twisted or kinked, so that when the roll set was again lowered the twisted portions were liable to be damaged or deformed. This type of slack I have for convenience termed "idle slack" because it occurs only when the rolls are in idle position. It is beyond the capacity of the ordinary slack take-up means, and in the present application I disclose and claim novel and improved means for maintaining the tapes under moderate tension even when the rolls are raised.

Proceeding now to a more specific description

of the invention, a frame 15 supports the heated chest 11. The rolls 10, padded and covered in conventional fashion, are journaled at each end in pressure bars 16, the journal means being vertically movable in slots 15a (Fig. 1) in the frame. The pressure bars 16 are moveable up and down by links 17 and 18, respectively at the left and right ends of Figs. 1 and 2. The links are pivotally carried on eccentrics 19 and 20, these being rotatable by suitable operator-controlled means (not shown) for applying variable degrees of pressure between the rolls and chest or for raising the rolls entirely out of contact with the chest, as seen in Fig. 2.

The flatwork to be ironed is disposed on the travelling feed ribbons 22, and proceeds beneath the stripper tapes 12 to the right end of the chest 11, and then travels clockwise around the chest end and between the chest and a movable apron 23, being carried frictionally by the apron along the polished bottom of the chest toward the front (left) end. At this point the article goes between apron 23 and another apron 24 and is carried to the rear (right) end and delivered there for folding or further disposal, as desired. Certain apron-carrying rolls are indicated in the drawings, the use, construction, and operation thereof being conventional, so that more specific description is not necessary. The rolls 25 and 26 are made adjustable, for proper apron tension, and they are rotatably journaled in a pair of laterally opposed swingable wings or brackets 27, one such bracket being shown.

Brackets 27 are pivotally supported at 28 on the frame 15, and, when swung, carry the apron tension rolls 25, 26 through an arcuate path of travel so as to apply or release tension on the aprons 23, 24. Movement of the brackets 27, when desired, is effected by rotation of heart-shaped cams 29 upon which ride rollers 30 carried on the brackets. In Fig. 1 the roll is on the cam rise, and in Fig. 2 it is on the cam drop. Downward (clockwise) swing of brackets 27 releases apron tension, and upward movement of brackets 27 applies tension to the apron as will appear. Release of apron tension is desirable when the ironer is inactive to prevent scorching of that portion of apron 23 which is in contact with the heated chest. The cam 29 operates synchronously with eccentric 20 so as to release 50 apron tension as the roll assembly is raised.

A roll 33 is swingably carried on arms 34, said arms being pivoted on the frame at 35 (Fig. 5). This roll cooperates with apron roll 25 to loosen or tighten apron 23 which runs around roll 33 55 and under the chest. A link 36 connects arm 34 with bracket 27, being pivotally connected to the arm at 37 and to the bracket at 38, so that swing of the bracket applies or releases tension to apron 23 through responsive swing of roll-carrying arm 34.

I have taken advantage of the swingable movement of roll 33 and arm 34 to take up idle slack in the stripper tapes 12, as follows.

I have previously indicated that the stripper tapes passed around rod 14 at the rear end of the ironer. In former construction this rod was fixed on the pressure bars 16. I here provide a pair of lugs or brackets 40 which are attached to arm 34 and between which the rod 14 is disposed. It 70 will be apparent that when the rolls 10 are raised and the apron tension bracket 27 swings clockwise downwardly, the arms 34 and rod 14 swing clockwise rearwardly and downwardly so as to take up most of the idle slack in tapes 12, as well

shown in Fig. 2. The remainder of the slack is continuously taken up by the transient slack device now to be described.

Such transient slack device comprises an arm 42 bifurcated at its tip end to conveniently carry the spool 13 previously mentioned, there being of course one arm and spool for each tape 12. Each arm 42 is pivotally mounted on a cross brace 43 which is attached at its ends to pressure bars 16. As here shown the pivotal mounting of the arm may be on a pivot pin 44 in a bracket 45 carried by cross brace 43, as best shown in Fig. 4. Disposed at the other side of pivot pin 44, away from spool 13, is a counterweight 46 which exerts a uniform tension in a clockwise direction (Fig. 4) on a stripper tape 12 and which is not subject to the disadvantages accompanying spring biased devices of the prior art. The upper flight of the stripper tapes descends from the spool, passes around a rod 47 fixed on side brackets 47a between pressure bars 16, and then to the right above the rolls 10, and down around bar 14 as previously described. The lower stripper tape flight descends from the spool, and passes to the left of the first roll 10 and then between said roll and the chest 11, also as previously described.

To meet varying conditions, such as the number of tandem rolls 10, various movable elements of the described slack takeup means may be adjusted to compensate for such variation. Those skilled in the art, upon studying the above disclosure, will realize that the amount of swing of arm 34 or of bracket 27 may be changed in various ways, such as by adjusting the length of link 35 or the height of the cam rise of cam 29, or by changing the distance between roll 33 and bracket pivot 28, etc.

From the above description it will be apparent that the present invention comprises means for taking up the major slack in stripping tapes resulting from raising of the rolls, and the minor slack resulting from transient causes during operation. It is further apparent that the means for taking up transient slack is effective at all times, and is maintained under uniform tension. Finally, it is apparent that the said slack take-up devices are simultaneously effective, and supplement each other, when the rolls are in idle position.

What is claimed is:

1. In an ironing machine of the type having an ironing chest and an ironing roll cooperating therewith between which chest and roll the work is passed for the ironing operation, and having an endless flexible stripping tape passed between the roll and the chest, the upper flight being returned above the roll, idle slack take-up means for said tape comprising, in combination, an endless flexible apron having a portion travelling adjacent said chest, means for moving said apron towards and away from said chest, and means engaging said tape and said apron-moving means for applying slack take-up tension to said tape when said apron is moved out of operating contact with said chest.

2. In an ironing machine of the type having an ironing chest and an ironing roll cooperating therewith between which chest and roll the work is passed for the ironing operation, and having an endless flexible stripping tape passed between the roll and the chest, the upper flight being returned above the roll, idle slack take-up means for said tape comprising, in combination, an endless flexible apron having a portion travelling adjacent said chest, apron-tensioning means

5

swingably mounted with respect to said chest and engaging said apron, and movable from tension-applied to tension-relaxed position, and means engaging said tape and said apron-tensioning means for applying slack take-up tension to said tape when said apron-tensioning means is moved to tension-relaxed position.

3. In an ironing machine of the type having an ironing chest and an ironing roll cooperating therewith between which chest and roll the work is passed for the ironing operation, and having an endless flexible stripping tape passed between the roll and the chest, the upper flight being returned above the roll, idle slack take-up means for said tape comprising, in combination, an endless flexible apron having a portion travelling adjacent said chest, apron-tensioning means swingably mounted with respect to said chest and engaging said apron, means for simultaneously moving said roll out of contact with said chest and for swinging said apron-tensioning means to tension-relaxed position, and means engaging said tape and said apron-tensioning means for applying slack take-up tension to said tape when said apron-tensioning means is moved to tension relaxed position.

4. In an ironing machine of the type having an ironing chest and an ironing roll cooperating therewith between which chest and roll the work is passed for the ironing operation, and having

10

15

20

25

30

6

an endless flexible stripping tape passed between the roll and the chest, the upper flight being returned above the roll, idle slack take-up means for said tape comprising, in combination, an endless flexible apron having a portion travelling adjacent said chest, apron-tensioning means swingably mounted with respect to said chest and engaging said apron and movable from tension-applied to tension-relaxed position, means for simultaneously moving said roll out of contact with said chest and for swinging said apron-tensioning means to tension-relaxed position, tape-tensioning means swingably mounted with respect to said chest and engaging said tape, and linkage means pivotally connected to said tape-tensioning means and to said apron-tensioning means and adapted to apply slack take-up tension to said tape when said apron-tensioning means is moved to tension-relaxed position.
